US0D1024357S

(12) **United States Design Patent** (10) **Patent No.:** **US D1,024,357 S**
(45) **Date of Patent:** **** Apr. 23, 2024**

(54) **POST SUPPORT**

(71) Applicant: **Gerald W. Newman**, Spangle, WA
(US)

(72) Inventor: **Gerald W. Newman**, Spangle, WA
(US)

(**) Term: **15 Years**

(21) Appl. No.: **29/816,455**

(22) Filed: **Nov. 22, 2021**

(51) **LOC (14) Cl.** **25-01**

(52) **U.S. Cl.**

USPC **D25/133**

(58) **Field of Classification Search**

(57) **CLAIM**

The ornamental design for a post support, as shown and described.

DESCRIPTION

FIG. 1 is a top, front perspective view of a post support;

FIG. 2 is a bottom, back perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the post support that form no part of the claimed design. The dot-dashed broken lines represent boundaries of the claimed post support and form no part of the claimed design.

1 Claim, 8 Drawing Sheets
